UNITED STATES PATENT OFFICE.

WILLIAM E. BRYANT, ROBERT DAVIDSON, AND GEORGE M. WOLCOTT, OF DETROIT, MICHIGAN, ASSIGNORS TO MICHIGAN LUBRICATOR COMPANY, OF DETROIT, MICHIGAN, A CORPORATION.

SIGHT-FEED LUBRICATOR.

SPECIFICATION forming part of Letters Patent No. 783,718, dated February 28, 1905.

Application filed August 4, 1904. Serial No. 219,475.

To all whom it may concern:

Be it known that we, WILLIAM E. BRYANT, ROBERT DAVIDSON, and GEORGE M. WOLCOTT, citizens of the United States, residing at Detroit, in the county of Wayne, State of Michigan, have invented certain new and useful Improvements in Sight-Feed Lubricators; and we do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to condensation-displacement sight-feed locomotive-lubricators of the balanced type; and it consists in the construction and arrangement of parts hereinafter fully set forth, and pointed out particularly in the claims.

20 The object of the invention is to produce a lubricator of the character described wherein the arrangement is such as to provide a cali-duct or heating-chamber at the top of the reservoir through the presence of which the lubricant may be maintained in a state of fluidity in climates where the lubricator is subjected to an extremely low temperature, at the same time providing in connection with said heating-chamber interior equalizing passage-ways within the parts of the lubricator, whereby the balancing of the lubricator may be effected and provision made for the passage of steam through said chamber and out the oil-

35 discharge ports to the several tallow-pipes which lead to the steam-chests of the cylinders and to the pump of the air-brake system, obviating the placing of equalizing-tubes upon the exterior of the reservoir, as commonly practiced, and overcoming the necessity of using many fittings and parts commonly employed, producing a lubricator which has few exterior connections and which is simple and compact.

40 The above object is attained by the structure illustrated in the accompanying drawings, in which—

Figure 1 is a vertical longitudinal section through a lubricator embodying our invention. Fig. 2 is a vertical section on line 2 2 5° of Fig. 1. Fig. 3 is a horizontal section as on line 3 3 of Fig. 1. Fig. 4 is a similar section as on line 4 4 of Fig. 1.

Referring to the characters of reference, 1 designates the body of the lubricator, within 55 which is located the oil-reservoir 2. Mounted upon the top of the body are the sight-feed features, which comprise the outside stems 3 and the middle stem 5, formed integral with said body and having therein the cylindrical 60 sight-chambers 4, through which the passage of the oil to the parts to be lubricated may be observed. The upper ends of said stems above the sight-chambers are hollow, as shown at 6, and leading from said hollow portions 65 are the oil-discharge ports 7, which pass through the feed-arms 8, to which the tallow-pipes 9 are connected.

The condenser 10 is mounted upon the central stem 5 and has communication at 11 with 70 the steam-supply pipe. Passing vertically through the condenser is a stand-pipe 12, whose upper end terminates in the steam-pipe, whereby a supply of dry steam is at all times afforded. Communicating with the lower end 75 of said stand-pipe is a passage-way 13, which extends downwardly through the stem 5 and communicates at its lower end with the cali-duct or steam-chamber 14, formed in the top of the reservoir, by which means a supply of 80 live steam is at all times present in said chamber, affording sufficient heat at the top of the reservoir to keep the oil which passes therefrom through the several sight-feed features in a high state of fluidity even in extremely 85 cold weather. In order to prevent the accumulation of water of condensation in said cali-duct or steam-chamber, provision must be made for maintaining a flow of steam there-through, which result is accomplished and the 90 equalization of the lubricator at the same time effected by means of steam-passages 15, extending vertically through the stems of the sight-feed features and communicating with

the oil-discharge ports 7, whereby a flow of steam through said chamber is maintained and the lubricator is balanced by reason of the fact that through the medium of said steam- 65
 5 equalizing passages boiler-pressure is present within the sight-feed chambers 4 to balance the pressure which is present in the body of the cup through the connection of the reservoir with the condenser by way of the passage 16, which extends downwardly through the middle stem 5 and the tube 17, communicating with the lower end of said passage and depending within said reservoir through which the water of condensation from the condenser 70
 10 is directed to the bottom of said reservoir, the flow of said water from said condenser being controlled by the valve 18. The oil flows from the reservoir to the several sight-feed chambers through the oil-ducts 19, which pass upwardly from the reservoir through the stems of the sight-feed features, the flow of oil therethrough being controlled by the valve 20. Communicating with the upper end of each of the oil-ducts 19 is an oil-feed nozzle 21, 75
 15 which extends within the sight-chamber and from which oil ascends in drops to the oil-discharge port 7 through the water which fills said chamber, as is common in the art. The flow of the oil is rendered visible by 80
 20 means of the opposed glasses 22, which are located in the opposite ends of the sight-chambers 4 and are confined within a sleeve 23, which screws into the ends of said chamber and carries the washers 24 and 25, between which the glasses are confined. 85
 25 Seated within the enlarged outer end of each of the oil-feed arms 8 is a plug 26, having an aperture 27 therethrough within the upper arc thereof. The plane of this aperture is 90
 30 above the bottom side of the tallow-pipe 9, so that the flow of steam through said tallow-pipe is prevented from drawing the water through the oil-port 7 and from between the glasses in the sight-chambers. Also communicating with the sight-chamber is a drain- 95
 35 duct 28, controlled by a valve 29, having an aperture 30 extending therethrough, whereby the water may be drained from the sight-chamber when desired. 100
 40 By means of the arrangement herein shown and described a constant flow of steam is maintained through the stand-pipe 12 and caliduct or chamber 14, thence by way of the equalizing-passages 15 through the oil-discharge 105
 45 ports 7, and thence through the tallow-pipes to the parts to be lubricated. This flow of live steam not only heats the lubricant at the top of the reservoir, but as well maintains a circulation which assists materially in carrying the oil freely through the tallow-pipes to the points of use, at the same time perfectly balancing the lubricator and obviating the use of exterior equalizing-tubes and all of the connecting parts incident to their employment, 110
 50

very materially reducing the cost of manufacture and presenting a compact lubricator wherein the detachable parts and exterior fittings are materially lessened. 115

Having thus fully set forth our invention, what we claim as new, and desire to secure by Letters Patent, is— 120

1. A lubricator comprising an oil-reservoir, a condenser, there being an oil-discharge passage leading from the reservoir, there being a steam-heating chamber in the reservoir, and there being an independent equalizing - passage connecting said chamber with the oil-discharge passage. 125

2. A lubricator comprising a condenser and oil-reservoir, there being an oil-discharge passage leading from the reservoir, said reservoir being provided with a steam-chamber through the medium of which the lubricant may be heated, a sight-feed feature in the oil-discharge passage, there being an equalizing - passage 130 connecting said chamber with the oil-discharge passage above said sight - feed feature, and there being communication between the source of steam-supply and said steam-chamber. 135

3. A lubricator comprising a reservoir, a condenser, said reservoir having a steam-chamber communicating with the source of steam-supply, a plurality of sight-feed features, there being an oil-feed passage for each sight-feed feature leading from the reservoir through the sight-chambers of said sight-feed features, and there being an equalizing - passage for each oil-discharge passage, each equalizing - passage leading from said steam-chamber and communicating with its respective oil-discharge passage, and there being a condensation - passage connecting the condenser with the bottom of the reservoir. 140

4. A lubricator comprising a condenser, an oil-reservoir, a plurality of sight-feed features mounted upon the reservoir and communicating therewith, oil-discharge passages also communicating with said sight-feed features, the oil-reservoir having a steam - caliduct, there being through each of the sight-feed features 145 an equalizing - passage connecting said caliduct with the oil-discharge port, there being a steam - passage through one of the sight-feed features connecting the steam - space of the condenser with said caliduct. 150

5. A lubricator comprising a condenser, an oil-reservoir, a steam-chamber for said reservoir, sight - feed features mounted upon the reservoir, each having a sight-chamber communicating therewith, there being an oil-discharge passage leading from each chamber, there being a steam - passage connecting said steam-chamber with the steam - space of the condenser, and there being an interior equalizing - passage connecting said steam-chamber 155 independently with each of the oil-discharge passages. 160

6. A lubricator comprising a condenser, an

oil-reservoir, said reservoir having a steam-heating chamber in the top thereof, a sight-feed feature mounted on the top of the reservoir above said chamber, there being a direct 5 passage for the oil from the reservoir through the sight-chamber in said sight-feed feature, there being an oil-discharge passage-way communicating with said sight-chamber, and there 10 being an equalizing passage-way within the sight-feed feature leading from said steam-

chamber in the top of the reservoir to said oil-discharge passage.

In testimony whereof we sign this specification in the presence of two witnesses.
